(57) **CLAIM**

The ornamental design for an archery bow rotatable member, as shown and described.

DESCRIPTION

FIG. 1 is an angled front-top view of a first (e.g. right-handed) embodiment of the archery bow rotatable member. FIG. 2 is an angled bottom-rear view of the first (e.g. right-handed) embodiment of the archery bow rotatable member.

FIG. 3 is a top view of the first (e.g. right-handed) embodiment of the archery bow rotatable member.

FIG. 4 is a bottom view of the first (e.g. right-handed) embodiment of the archery bow rotatable member.

FIG. 5 is a back view of the first (e.g. right-handed) embodiment of the archery bow rotatable member.

FIG. 6 is a front view of the first (e.g. right-handed) embodiment of the archery bow rotatable member.

FIG. 7 is a left side view of the first (e.g. right-handed) embodiment of the archery bow rotatable member.

FIG. 8 is a right side view of the first (e.g. right-handed) embodiment of the archery bow rotatable member.

FIG. 9 is an angled front-top view of a second (e.g. left-handed) embodiment of the archery bow rotatable member. FIG. 10 is an angled bottom-rear view of the second (e.g. left-handed) embodiment of the archery bow rotatable member.

FIG. 11 is a top view of the second (e.g. left-handed) embodiment of the archery bow rotatable member.

FIG. 12 is a bottom view of the second (e.g. left-handed) embodiment of the archery bow rotatable member.

FIG. 13 is a back view of the second (e.g. left-handed) embodiment of the archery bow rotatable member.

FIG. 14 is a front view of the second (e.g. left-handed) embodiment of the archery bow rotatable member.

FIG. 15 is a right side view of the second (e.g. left-handed) embodiment of the archery bow rotatable member; and,

FIG. 16 is a left side view of the second (e.g. left-handed) embodiment of the archery bow rotatable member.
